UNITED STATES PATENT OFFICE.

ALBERT H. WEIS, OF NYACK, NEW YORK, ASSIGNOR TO METROPOLITAN SEWING MACHINE CORPORATION, OF NYACK, NEW YORK, A CORPORATION OF DELAWARE.

BINDER OR FOLDER FOR SEWING MACHINES.

Application filed March 29, 1922. Serial No. 547,666.

To all whom it may concern:

Be it known that I, ALBERT H. WEIS, a citizen of the United States, residing at Nyack, in the county of Rockland and State of New York, have invented certain new and useful Improvements in Binders or Folders for Sewing Machines, of which the following is a specification.

This invention relates to the method and mechanism for applying a pile binding strip to an article of wearing apparel, and particularly to folders or binders for sewing machines adapted for use in guiding and folding what is known in the trade as a mohair or plush binding used on various kinds of wearing apparel, such, for instance as felt slippers or shoes, an object of the invention being to provide a mechanism for applying the binding to the edges of the material in an efficient, facile, and relatively rapid manner. As a result of the present invention therefore, the securing or stitching of the binding to the material is accomplished readily and effectively at a minimum of expense.

Other objects of this invention will appear in the following description thereof, reference being had to the accompanying drawings forming a part of this specification, wherein like reference characters indicate corresponding parts in the several views and wherein Fig. 1 is a perspective view of a sewing machine having my invention applied thereto; Fig. 2 is a detail sectional view of a kind of mohair or plush binding; Fig. 3 is a view illustrating by way of example a felt slipper with the mohair or plush binding applied thereto; Fig. 4 is a cross section illustrating by way of example a piece of felt with the mohair or plush binding stitched thereto; Fig. 5 is an end view of my folder, illustrating the manner in which the raw edges of the mohair or plush binding are first folded over and then under preparatory to the stitching operation; Fig. 6 is a perspective view of the folder applied to the work plate of a sewing machine, and illustrates how the folder is located in a trough of the work plate so as to have the lower jaw of the folder project into a cut-out portion of the throat plate adjacent to the needle hole thereof so as to properly control the bottom folded edge of the binding; Fig. 7 is a front elevation of the folder, parts being broken away to show the chan-

nel or trough guiding means for the mohair or plush of the binding; Fig. 8 is a vertical section taken on line 8—8 of Fig. 7 and in the direction of the arrows; Fig. 9 is a vertical section taken on line 9—9 of Fig. 7 and in the direction of the arrows; Fig. 10 is a detail view of the mohair or plush binding, illustrating the manner in which the mohair or plush bristles of the nap or pile are brushed back under the control of the folder, how the raw edges thereof are folded over and under during the passage of the binding strip through the folder, and how it is turned at right angles to the initial direction of this movement as it is fed up to the stitching mechanism of the sewing machine; and Fig. 11 is a detail view illustrating the action of the four motion top and bottom feed and the automatic presser foot acting upon the binding to feed it through the machine.

The present folder may be designated as a combination right angle binder or folder, the same being adapted particularly for guiding and folding mohair or plush binding, whether it be elastic or inelastic, or whether such binding be cut on the straight or on the bias, the present mechanism handling both kinds with equal facility.

Heretofore mohair or plush binding was applied to the edges of felt slippers, or other apparel by means of a stapling machine for applying metal staples, the binding being folded over the edge of the article and the mohair or plush being brushed aside by hand, while the staples were inserted to fasten the binding in place. The use of these staples was objectionable because they would often protrude from the binding and come into contact with the foot or injure the stocking covering the foot of the wearer. Such staples were placed at suitably spaced intervals to hold the binding in place, but difficulty was encountered in obtaining a smooth finish where the binding was applied to the curved or irregular edges of the articles, such as around the tongue of felt shoes or at the upper curved edge of the heel thereof.

Attempts have been made to stitch such binding to the edges of slippers, shoes, etc., by first laying the binding with the mohair or plush face thereof against the article, then placing a row of stitches along the edge of the article and the binding and securing

the latter in place. After this operation the binding has one of its edges stitched all around the edge of the slipper or shoe, and thereupon by folding the binding over the 5 edge of the shoe or slipper by hand, the opposed raw edge of the binding was folded under at the time of a second stitching operation, thus securing such second folded edge of the binding to the slipper or shoe. 10 Great difficulty was encountered in accomplishing these stitching operations, particularly in the second operation due to the fact that the stitches would pass through the mohair or plush on the opposite side of the 15 binding; that is, the bottom side of the binding which cannot be seen during the second stitching operation, such stitches binding and stitching down the bristles and thereby rendering the work defective. 20 The foregoing difficulties and disadvantages are overcome by virtue of my invention, the present folder being provided with means to receive the mohair or plush and so control it during the folding or 25 stitching of the binding to the article, that there is no possibility of the mohair or plush being caught by the stitches. Furthermore, the construction is such that 30 stitches will be placed in close proximity to the mohair or plush so that the stitches will be practically concealed on the finished article.

While the present folder is adapted for use on various types of sewing machines 35 for the purpose of binding such articles of irregular form as slippers, shoes, hats, caps, and the like, the sewing machine herein shown is constructed with a four motion top and bottom feeding mechanism operative to properly clamp and feed the binding. 40

In the drawings, the sewing machine frame 1 carries the usual top shaft for driving the needle bar and the top feed mechanism, and the base 2 of the machine frame carries the bottom shaft for operating the bottom feed mechanism as well as the looper which coacts with the needle for making the stitches. Detailed description 45 of the sewing machine parts is deemed unnecessary since the same are described in Patent 1,222,339 to J. P. Weis, dated April 10, 1917.

The cloth plate 3 of the sewing machine 55 is provided with a slot 4 to provide a passage way for the binding 5, the slot having an angular portion 4 extending to the side of the cloth plate 3. The folder, generally indicated at 6 is supported by a 60 bracket 8 which is secured to the cloth plate 3 by means of screws 7 in such a manner as to permit the necessary adjustment of the binder with respect to the stitching position. The throat plate 9 is secured to the 65 front end of the cloth plate 3. This throat

plate is provided with a feed slot 10 through which the bottom feed 11 operates, and also with a needle hole 12. Just in front of the needle hole the throat plate is cut out at 13 to receive the lower jaw 70 of the binder. A guiding finger 14 is adjustably screwed to the throat plate by screw 15, the executant end 16 of the guiding finger being bent upward and over, or offset in order to leave sufficient space between the end thereof and the top surface 75 of the throat plate for the passage of the folded edge of the bottom portion of the binding. By adjusting this finger laterally on the throat plate, the bite or margin of 80 the penetration of the needle through the bottom portion of the binding can be controlled or varied to suit the conditions under which the machine is worked.

Co-acting with the bottom feed 11 is the top feed 17 having the usual four motions to properly clamp and feed the top of the binding at a speed uniform with that of the bottom of the binding. An automatic presser foot 18 is provided which has an up and down movement to clamp the work, as the needle is passing through the same, and to be lifted from the work during the movement thereof under the action of the feeds. The eye-pointed thread carrying needle 19 operates in the usual manner and cooperates with a suitable looper (not shown) located underneath the throat plate for forming the stitches. Referring to Figs. 4, 5, and 11, the folded edge of the binding at the top is indicated at 20, the bottom folded edge at 21, the felt or goods to which the binding is stitched at 22, and the mohair or plush at 23.

My improved folder is constructed of metal so shaped and assembled as to form a structure having a channel or trough extending a suitable distance throughout its length and centrally thereof for controlling the mohair or plush bristles of the binding. The folder is supported by a back wall or brace 24 secured to the angle bracket 8, the back wall or brace being attached to the folder in any suitable manner. The entrance end 25 of the folder is elongated 115 in form having an exterior shape similar to a flattened loop.

The upper and lower inner margins 26 and 27 are closed in to form therebetween a rectangular trough 28. This trough is for the reception of the mohair or plush bristles of the binding, and is of suitable width and depth to provide free passage of the binding therethrough. The raw edges of the binding project into the spaces 29 and 30. This entrance end of the folder may be made if desired of a single piece of flat metal with the margins 26 and 27 built therein by inserts, or otherwise, the free edges of such bent metal being secured to 120 125 130

gether by another flat piece of metal 31, which may form a portion of the front wall of the folder. For a suitable distance of its length the entrance end of the folder is 5 straight as shown from 32 to 33 in Fig. 7 to form a guiding portion suited to the width of the binding strip and to control the same as it enters the folder. The back wall 43 of the folder is cut out or notched at 34 and 35 and extending from these points the outer edges 36 and 37 of the inwardly curved back wall 43 are bent forwardly and tapered or inclined in the direction of their length so as to form overhanging, inclined or funnel-shaped folding portions, which assist in giving the initial folds 38 and 39 to the raw edges of the binding. These bent portions 36 and 37 have extending tabs 40 and 41 secured to the front concave convex wall 42, and it will be seen that the portions 36 and 37 so overhang or overlap in spaced relation the inner edges of the wall 42 as to provide a space between such overlapping portions and also a space 25 between the curved front wall 42 and the correspondingly curved back wall 43 for the free passage of the binding therethrough. The front wall 42 is provided with an elongated slot 44 in order to facilitate starting the binding through the folder. This front wall is also notched or cut out at 45 adjacent to notched portions 34 and 35. The back wall 43 is provided with inwardly extending projecting ribs 46 and 47, forming a continuation of the trough 28 extending from the entrance end of the folder to a point adjacent to the delivery end of the folder. These ribs may vary in height in order to suit the character of the 40 binding, as for instance if the bristles are long, the channel or trough of the folder is accordingly varied in depth. The ribs are also tapered and spaced apart according to the nature of the work, the purpose being 45 to provide space for the passage of the mohair or plush bristles, and at the same time provide just sufficient space between the free edges of the ribs 46 and 47 and the inside face of the front wall 42 for the passage of the binding.

The delivery end of the folder terminates in a substantially U-shaped throat 48 having the central axis thereof extending in a direction substantially parallel to the longitudinal axis of the binder. This throat is provided with a wire edge 49 which terminates in hook shaped ends 50 and 51, the purpose of the wire edge being to form a wear resisting surface over which the binding passes while making the right angle turn or change in its direction of feed or movement. The bent ends 50 and 51 of the wires operate to control the folded edges of the binding and to maintain such edges in proper position relative to the needle.

Secured to the rear wall of the top overhanging portion 36 of the folder is an adjustable guide 52 held in position by screws 53. The forward end of this guide 52 has an offset or bent portion 54, the free end 70 of which terminates in a guide hook 55. This guide hook 55 is located close to the hook 50 in rear of and slightly lower than the same (see Figs. 5 and 7) so as to also assist in controlling the top folded edge of 75 the binding as it passes from the folder to the needle.

The bottom folded edge of the binding is controlled by the offset overhanging end 16 of the guide 14 secured to the throat 80 plate. The delivery end of the holder and the hooks 50 and 51 as well as the guide hook 55 are positioned as close to the guide 14 as possible so that there is no liability 85 of the binding being forced out of the path of the needle when stitching around sharp curves of semi-rigid work, such as felt and the like. By adjusting laterally either of the guides 14 or 52, the top or bottom edge 90 of the binding may be controlled so as to bring the line of stitches in proper relation with the respective folded edges of the binding.

It will be particularly noted that the top 95 guide hook 55 not only acts as a guiding means for controlling the upper folded edge of the binding but also operates by virtue of its hooked formation to brush aside or deflect the bristles of the mohair or plush to prevent them from getting into the path 100 of the needle.

Referring to Fig. 10 it will be readily seen how the present mechanism operates in effectually controlling the bristles of the binding while the binding is passing through the folder to the stitching mechanism. The binding enters the folder in substantially a vertical straight position between the points 56 and 57. The bristles of the nap or pile 23 of the binding are laid over or deflected by ribs 46 and 47 while passing through the folder as represented at 58, the initial folds 38 and 39 then being formed. Due to the funnel or tapered shape 105 of the folder the bristles will be laid over or deflected increasingly upon approaching the position 59 where the second folding as indicated at 60 is accomplished. Upon reaching and passing through the throat 48 the direction of movement of the binding is changed at right angles, the top and bottom folded edges are folded into substantial juxtaposition over the edge of the goods 22 as shown in Fig. 4 and the binding is turned 110 inside out. After it makes the right angle turn it leaves the folder at the stitching position 61. The bristles 23 then assume their normal position on the top side and edge of the binding as indicated at 62. The bottom bristles 115 it will be noted are 120 125 130

dragged along over the top surface of the throat plate, as indicated at 63, in Fig. 11, and are thus effectually deflected so as to be entirely out of the way of the needle.

5 It is to be noted that the bottom and top feed as well as the presser foot are very small, each of the feeds having but several teeth so as to act upon the binding as close to the needles as possible, thus enabling the 10 stitching to be carried around sharp curves or over irregular pieces of work without difficulty, and at the same time keeping the binding under control and preventing the bristles of the mohair or plush from getting 15 into the path of the needle.

The location of the folder is approximately central with the line of feed of the work, that is to say, one half of the folder is located below the top surface of the cloth

20 and throat plate for easy entrance of the work and for permitting better control of the binding, this top surface of the throat plate being indicated by line 69 in Fig. 5.

The character and construction of the 25 mechanism is such that there is a minimum of bulk and parts at and around the stitching position. Thus, since the folder is located directly at the stitching position, such work as applying bindings to slippers, shoes, 30 etc., can be done with great rapidity as there is nothing to interfere with the handling of the work.

In Fig. 3 is illustrated the manner of 35 application of the mohair binding to a slipper 64. It will be understood that the binding may be applied to a slipper, or any similar article, either before or after the sole has been applied, and that the commencement of the application of binding 40 may, if desired, be at the heel 65 of the slipper. The binding is then stitched around to the point indicated at 66 where a sharp turn is made. It is then stitched around the tongue or front portion 67 and 45 then around to the opposite cut or sharp turn, and then back around the opposite side 68 and ending by overlapping the binding at 65 where it is cut off. The end may then be tacked down by a separate stitching 50 operation. Of course the starting and ending of the stitching operation in applying the binding to the article can begin or end at any convenient position. When the binding is applied to the edges of the slipper as shown, 55 it assumes the form shown in Fig. 4, where it will be seen that the bristles spread out so as to overhang the stitched margin and thereby conceal both sides of the line of stitches.

60 I claim as my invention:

1. A binder adapted to receive a pile binding, and having means effective to deflect the pile of the binding away from the line of stitching during the attachment of 65 an edge thereof to an article of apparel.

2. A binder adapted to receive a pile binding, and having means effective to deflect the pile of the binding away from the line of stitching at both edges of the binding during the attachment thereof to an 70 article of apparel.

3. A binder adapted to receive a pile binding, and having means effective to deflect the pile of the binding away from the line of stitching during the attachment of 75 an edge thereof to an article of apparel, and also having means for turning the binding inside out.

4. The combination of a binder adapted to receive a pile binding, and means effective to deflect the pile of the binding away from the line of attachment during the attachment thereof to an article, said means comprising a hooked member.

5. Binding mechanism comprising the 80 combination of means for receiving a pile binding, means for folding an edge of the binding, means for folding the body of the binding to apply said folded edge to an article, and means for deflecting the pile of 90 the binding away from the line of attachment.

6. Binding mechanism comprising the 95 combination of means for receiving a pile binding, means for folding both edges of the binding, means for folding the body of the binding to apply said folded edges to an article, and means for deflecting the pile of the binding away from the line of attachment at both edges of the binding.

7. Binding mechanism comprising the 100 combination of means for receiving a pile binding, means for folding an edge of the binding, means for turning the binding inside out to apply said folded edge to an 105 article, and means for deflecting the pile of the binding away from the line of attachment.

8. Binding mechanism comprising the 110 combination of means for receiving a pile binding, means for folding an edge of the binding, means for folding the body of the binding to apply said folded edge to an article, and means for deflecting the pile of 115 the binding away from the line of attachment and also effective to guide said folded edge.

9. A binder adapted to receive a pile binding and having means for applying the edges of said binding to the opposite sides of an article, said binder having means effective during the movement of the strip in different directions relative thereto to fold the edges thereof and to fold said folded edges over the edge of the article, and a 120 hooked guide member located in position to coact with a folded edge and to deflect the pile of the binding away from the line of stitching during attachment.

10. A folder or binder for sewing ma- 125

chines adapted to receive a pile binding, and comprising means effective during the feed of the binding to fold the edges thereof, means for confining the pile of the binding, means effective upon the feed of the binding in a transverse direction to fold the binding and apply the folded edges thereof to an article, and means for deflecting the pile of the binding away from the line of attachment.

11. A folder or binder for sewing machines adapted to receive a pile binding, and having means effective during the feed of the binding to fold the edges thereof and control the pile of the binding, said folder also having means effective upon the feed of the binding in a transverse direction to fold the folded edges thereof over the edge of an article, and to deflect the pile of the binding, and said means including a hooked guide member.

12. In a sewing machine the combination of a support, a folder or binder carried thereby for receiving a pile binding and having means effective during the movement of the binding relatively thereto for folding the edges and controlling the nap of the binding, said folder also having means effective upon movement of the binding in a transverse direction to fold the folded edges thereof over the edge of an article, means for securing said folded edges to the article, and means for deflecting one edge of said nap out of the path of said securing means, said support acting to deflect the opposite edge of the nap.

13. The combination of means for receiving and guiding a plush binding, means for automatically folding the edges thereof and simultaneously applying both folded edges thereof to an article, means located in position for attaching said folded edges to the article along the edge of the nap of the binding, and means for holding the nap away from the line of attachment.

14. The combination of a binder adapted to receive a pile binding, and means effective to guide the edge of the binding, and also to deflect the pile of the binding away from the line of attachment during the attachment thereof to an article.

15. The method of applying and attaching a pile binding strip to an article which consists in simultaneously folding both edges of the binding over the edge of the article, feeding the article and binding to an attaching mechanism, and deflecting the pile of the binding away from the line of attachment.

16. The method of applying and attaching a pile binding to an article which consists in simultaneously folding both edges of the binding over upon the article, feeding the article and binding to an attaching mechanism, and brushing back or deflecting

simultaneously both edges of the pile of the binding away from the line of attachment.

17. The method of applying and attaching a plush or pile binding to an article which consists in folding the edges of the binding, then folding said folded edge over the edge of an article, presenting the binding and article to a stitching mechanism, and deflecting the pile or nap of the binding away from the line of stitching.

18. The herein described method which consists in applying a pile binding to an article, deflecting or brushing back progressively a part only of an edge of the pile away from the line of attachment, and at the same time attaching the edge of the binding to the article substantially along the edge of the pile.

19. The herein described method which consists in folding the edging of a pile binding as it is fed in one direction, then folding said folded edge over upon an article as the binding is fed in another direction, feeding the same to the stitching mechanism of a sewing machine, and brushing back or deflecting the pile of the binding away from the line of stitching so that the pile will be free of the stitching and the binding will be secured to the article substantially along the edge of the pile.

20. An attachment of the class described comprising a body comprising a pair of opposed side walls forming a lengthwise extending passageway therethrough for receiving a pile binding strip, one of said walls having a pair of projecting portions extending transversely into said passageway and forming a relatively shallow portion for receiving the free edge of the strip and a relatively deep portion for receiving the pile of the strip.

21. Binder mechanism for pile binding strips comprising a hollow member having a guide channel for limiting the spreading of the pile, means for folding an edge of the strip, and means for folding said folded edge over upon an article, means for guiding the folded edge and means for deflecting the pile, one of said last means being fixed and the other adjustable.

22. Binder mechanism for pile binding strips comprising means for applying an edge thereof to an article, and means for deflecting the pile of the strip away from the edge of the pile.

23. Binder mechanism for pile binding strips comprising means for applying an edge thereof to an article, and adjustable means for deflecting the pile of the strip away from the edge of the pile.

24. Binder mechanism for pile binding strips comprising a body having a relatively shallow channel extending lengthwise thereof and a relatively deep channel, and a pair of spaced projecting portions extending

lengthwise of the body for separating said channels.

25. Binder mechanism for pile binding strips comprising means for applying an edge thereof to an article, and fixed and adjustable means for guiding said edge, one thereof effective to deflect the pile of the strip away from the edge of the pile.

26. A binder for pile binding strips, com-

prising a hollow body having a channel provided with means for folding the edge of the strip over upon the body of the strip, said body also having a channel for confining the pile of said strip.

Signed at Nyack, N. Y., this 27th day of 15 March 1922.

ALBERT H. WEIS.
